UNITED STATES PATENT OFFICE.

ARTHUR W. LE BOEUF, OF WOONSOCKET, AND JOSEPH B. ARMITAGE, OF PAWTUCKET, RHODE ISLAND, ASSIGNEES TO ELECTRIC COMPOSITOR COMPANY, OF NEW YORK, N. Y., A CORPORATION OF NEW JERSEY.

ELEVATOR MECHANISM.

1,080,569.

Specification of Letters Patent.

Patented Dec. 9, 1913.

Application filed December 15, 1911. Serial No. 665,912.

To all whom it may concern:

Be it known that we, ARTHUR W. LE BOEUF and JOSEPH BRADLEY ARMITAGE, citizens of the United States, and residents, respectively, of Woonsocket, in the county of Providence and State of Rhode Island, and Pawtucket, in the county of Providence and State of Rhode Island, have invented a certain new and useful Improvement in Elevator Mechanism, of which the following is a full, clear, and exact description.

This invention relates to the mechanism of a line casting machine, by means of which lines of matrices are raised from the casting position up and then along a distributing rail, and are properly presented to the distributing mechanism.

The object of the invention is to provide simple and durable mechanism which will properly perform these functions in such wise that the machine operator will not be obliged to await the complete distributing of one line of matrices before another line can be elevated and delivered onto and moved along the distributing rail.

The invention in its preferred form is shown in the accompanying drawings and is hereafter described in detail, and the construction and combination of parts which constitute the invention are defined by the appended claims.

In the drawing, Figure 1 is a front elevation of so much of a linotype machine as shows the visible parts thereof which are involved in the present invention. Fig. 2 is a rear view of the auxiliary line carrier and some associated mechanism. Fig. 3 is a sectional side elevation in the plane of the bent line D—D on Fig. 1. Fig. 4 is a full sized rear view of the operating mechanism for the elevator and line carriers when the rear cover of the inclosing casing has been removed. Fig. 5 is a sectional side elevation in the plane indicated by line B—B on Fig. 6. Fig. 6 is a plan view of the operating mechanism in said casing,—the casing being sectioned in the plane indicated by line C—C on Fig. 4. Fig. 7 is a sectional plan in the plane indicated by line A—A on Fig. 4.

Referring to the parts by numerals, 1 represents the elevator which is movable vertically on two vertical rods, 2, 2, as guides. The elevator is provided with a shelf 3

adapted to support a line of matrices. The elevator is connected with one leg of an endless chain belt 11, which runs over an upper driving sprocket 76 and a lower idler sprocket 13. When the elevator is in its uppermost position its shelf 3 is alined with and in substantial contact with the left end 55 of the distributing rail 16 which is near the top of the machine.

The line carrier slide 4 is movable horizontally in guideways just behind the horizontal distributing rail 16. It is connected 65 with the upper leg of an endless sprocket chain 12 which runs around a driving sprocket 95 at its left end and around a suitable idler sprocket at its right end, which idler sprocket is not shown. The line carrier slide has on its front side a yielding pressure plate 5 which extends over the distributing rail, so as to be able to engage with a matrix line thereon.

So much of the mechanism as has been described is old in a variety of arts. Much of the mechanism to be described is inclosed in a case 30 fixed to the upper left hand corner of the machine frame, which case has a removable rear cover 31.

The driving clutch 35 has on its front face, within the case 30, the ratchet clutch jaws 35^a, and it has also a rearwardly extended cylindrical part 35^b which is rotatably mounted in a bearing in the case. The 85 driving pulley 34 is fixed to the rear end of this cylindrical part. A starting clutch shaft 41 is alined with the driving clutch, being mounted at its front end in the casing and at the rear end in the end of the driving clutch.

The starting clutch 40 is a sleeve which has a feather and groove connection with the starting clutch shaft 41; and it has ratchet jaws 40^a for engagement with the 95 ratchet jaws 35^b of the driving clutch, and peripheral gear teeth 40^b. A spring 43 acts, when permitted so to do, to move the clutch member 40 endwise on the shaft 41 so as to cause the interlocking engagement of the 101 jaws 40^a and the jaws 35^b. This clutching movement of the clutch member 40 is prevented by the engagement of a spiral cam surface 40^c on said clutch member 40 with a pin 45 which is carried by one arm 44^a of a 105 three arm lever 44. Another arm 44^b of

this lever has a toe 44^c which is provided to go into a notch 47^a in a disk 47 fixed to the cam shaft 56. The third arm 44^d of this lever lies beneath a rearwardly extended 5 arm of the starting rod lever 49. This lever has a sleeve 49^a by means of which it is pivoted to fixed bracket arms 30^a. It is by pushing upward on the forwardly extended arm of the lever 49 that the mechanism is 10 set in operation. A long downwardly extended starting rod 48 is pivoted to front arm of said lever 49; and its lower end may be fixed to mechanism for moving it upward; or the operator may take hold of it 15 and move it upward when desired. The resultant movement of the lever 49 will cause the rearwardly extended arm thereof to rock the starting lever 44 and thereby (1) withdraw pin 45 from its engagement with 20 the cam surface 40^c on the clutch member 40, whereupon the spring 43 will move said clutch member along shaft 41, and cause it to interlock with the clutch member 35; (2) will also withdraw toe 44^c from the notch 25 47^a in disk 47. The engagement of the two clutch members 35 and 40 will cause the shaft 41 to begin to rotate, and will permit the cam shaft 56 to be rotated by the mechanism to be described, intermediate of it and 30 the starting clutch shaft 41.

The elevator shaft 65 is mounted in bearings near the top of the case, and it has secured to its front end an elevator driving sprocket 76. In the particular construction 35 shown, this driving sprocket loosely embraces a sleeve 77 which is keyed to the shaft 65, and lies between a flange 77^a on sleeve 77 and a friction disk 78. A spring disk 79 which embraces the shaft and bears 40 against the disk 78 is put under the proper tension by means of a nut 80, which screws onto the end of shaft 65 and thrusts a washer 81 against said spring disk 79. This frictional connection between the sprocket 45 76 and elevator driving shaft 65 is a safety expedient which will permit some rotation of shaft 65 independently of the sprocket in case anything should positively obstruct the movement of those parts which the sprocket 50 is intended to move. Embracing this elevator shaft 65, but disconnected therefrom are two gears 66, 67. The latter is always 55 in mesh with the gear 40^b on the periphery of the clutch member 40. The other gear 66 is in mesh with an idler gear 73 which in turn meshes with a pinion 42 fixed to shaft 41.

Between the two gears 66 and 67 is an 60 elevator clutch in the form of a sleeve 64 which is slidable on shaft 65, but has a feather and groove connection therewith. On one end of this sleeve is a cone clutch 64^a which is adapted to engage a conical recess in the adjacent face of the gear 67. On 65 the other end of the sleeve 64 are clutch jaws

64^b which are adapted to engage with clutch jaws 66^a on the adjacent end of the gear 66. It is obvious that when the shaft 41 is rotating, both gears 66, 67, on the elevator shaft must also rotate, but in opposite directions, but the elevator shaft does not turn until by the movement of the elevator clutch sleeve 64, one or the other of the gears 66, 67 is clutched to the elevator shaft 65.

In order to move the elevator clutch 64, a 75 fork lever 69 is provided, which lever is pivoted on a vertical pivot within the case. It has at its ends a swiveled fork 68 which engages the circumferential groove 64^c in the elevator clutch 64. It also carries a 80 friction roller 69^a which engages a face cam 72^a on the gear 72 which is fixed to the cam shaft 56. A spring 71 acts on this lever to hold the roller in contact with said cam. This lever 69 has also the function of withdrawing the elevator latch 82. This latch is a plunger sliding through a suitable hole in the casing wall. A spring 83 resists its backward movement and also moves it forward beneath the shoulder on the elevator, 90 when the elevator, in going up, has engaged the beveled end of said latch plunger and pushed it back. This latch carries an upwardly projecting pin 85^b which goes loosely into a hole in the lever 69, so that said lever, 95 by its movement rearward, may withdraw the latch. The pin 85^b is, as a matter of construction, fixed to a block 85^a which slides loosely on the stem 83, being held upon said stem by the head 85.

The cam shaft 56, before referred to, carries three cams, viz: the face cam 72^a, which is on the side of a large gear 72 which is fixed to said cam shaft; a line carrier cam 86, and the auxiliary line carrier cam 108; 105 and it also carries the notched disk 47 before referred to. The gear 72 meshes with an intermediate pinion 58, which is rigidly connected with an intermediate gear 57 which is rotatably mounted on the fixed 110 stub shaft 59. The gear 57 is in mesh with a pinion 41^c carried by the clutch shaft 41.

The cam 86 is for the immediate purpose of moving the segment frame 87 which is loosely hung on the elevator shaft 65. This 115 frame carries a friction roller 87^a adapted to be engaged by the cam 86. A spring 88 acts to swing the segment in the opposite direction to that in which the cam moves it. The gear teeth on this segment frame engage a pinion 92 which is fixed to gear 93, said gear and pinion being rotatably mounted on a shaft 99. The gear 93 is in mesh with a pinion 94 on the line carrier driving shaft 96 to which the line carrier driving 125 sprocket 95 is fixed. The line carrier sprocket chain 12 runs over this sprocket and over another sprocket which is not shown, to the right thereof, and, as before stated, the line carrier slide is fixed to the 130

upper leg of this sprocket chain. The other cam 108 is for operating the auxiliary line carrier. This cam engages with a friction roller on the auxiliary line cam lever 109; 5 and a spring 110 acting on the lever, moves it in the opposite direction. A link 111 connects this lever 109 with another lever 112, which is connected by a link 113 with the auxiliary line carrier, and particularly with 10 a slide 20 which forms a part thereof.

Whenever the elevator rises, carrying with it a line of matrices, this line is swept off the elevator onto the distributing rail by the line carrier, and along said rail until 15 the foremost matrix in a line comes against a stop 115, which is a part of the distributing mechanism. This distributing mechanism, although no part of the present invention, includes means by which the matrix at the 20 right end of the line is segregated from the line and sent along to its appropriate magazine. The line carrier being spring-actuated will move the line to the right whenever the right end matrix is removed so 25 that the next matrix will come against said stop and be in a position to be segregated. But it frequently happens that before this line has been entirely distributed, another assembled line of matrices will have been 30 put onto the elevator in readiness to be taken up to the distributing rail. In order that the distribution of the matrix line may be continued, while the line carrier goes to the left in order to be in the proper position 35 when the elevator comes up, the auxiliary line carrier referred to is provided. This includes a slide 21, which is movable in a suitable horizontal guideway below the distributing rail. The sliding bar 20, before 40 mentioned as connected by link 113, with lever 112, is supported on the slide in such wise that it is permitted to move horizontally a limited distance only, before imparting its movement to the slide. It has 45 a horizontal slot 20^a through which projects a stud 21^a fixed to the slide, and it has also a stud 20^b which projects through a horizontal slot 21^b in the slide. The right end of the link 113 is pivotally connected with the 50 rear side of the sliding bar 20.

Pivoted to the front side of the slide are two parallel links 22, 23, to the right ends of which are pivotally connected the auxiliary line carrier push bar 24. This projects upward and passes into and may pass 55 through a vertical slot 16^a in the distributing rail 16. The upper of the two parallel links has at its left end a downwardly extended finger 22^a adapted to be engaged by the head 60 of a stud 20^b which as stated is fixed to the sliding bar 20. A spring 25 acting upon the upper link 22 tends to swing it so as to carry the auxiliary line carrier push bar 24 up through the slot in the distributing rail 65 and behind a line of matrices thereon. But

when the sliding bar is moved to the left, the head of stud 20^b will strike the finger 22^a of the upper link 22 and so rock it as to draw the auxiliary line carrier push bar 24 down below the top of the distributing rail. 70 When the sliding bar is moved to the right, it carries the head of stud 20^b out of engagement with said finger, whereupon the spring 25 rocking the link 22 will carry the push bar 24 up so that its upper end is 75 above the top of the distributing rail, so that it may engage with a matrix resting upon said rail. The power to rock lever 109 in the direction which carries the auxiliary line carrier to the left comes from the cam 80 108 which, as stated, engages said lever 109 and swings it. When this cam has, through the described mechanism, moved said auxiliary line carrier mechanism to the left, the cam releases its engagement with said lever, 85 whereupon a spring 115 moves the lever in the contrary direction. The spring 27 is fixed to the auxiliary line carrier slide, and by pressing against the adjacent fixed frame member, acts as a brake or drag which 90 makes it certain that said slide shall not move until after the sliding bar 20 has moved relatively to said slide, as before explained.

The described mechanism operates as follows: When this mechanism is at rest the cam 86 is not engaging the segment frame 87, and therefore this frame, under the influence of the spring 88 is, through the train of mechanism described, acting on the line 95 carrier, to move it to the right, and thereby keep the matrix line moving along the distributing rail toward the distributing mechanism. The cam 108 is, however, acting upon lever 109, and holding it and the 100 auxiliary line carrier mechanism at the extreme left ends of their paths.

The mechanism is at rest because the pin 45 is engaged by the high part of the spiral cam surface 40^c on the starting clutch, 110 whereby said starting clutch is held out of engagement with the driving clutch. When, now, the operator gives the upward movement of the starting rod 48 and, consequently, rocks the lever 49, this latter lever 115 will rock the three armed lever 44, thereby releasing the cam shaft from restraint, and (2) withdrawing pin 45 from engagement with the spiral cam 40^c, which permits the starting clutch 40 to be moved by its spring 120 43 into clutching engagement with the driving clutch 35. The shaft 41 is thereby caused to rotate, and it, through the described train of mechanism, rotates the cam shaft, which thereafter continues to turn 125 until it has made one complete revolution. At the end of that time the toe 44^c will drop into notch 47^a; and, as the result of rocking of lever 44, the pin 45 will move into the path of the spiral cam 40^c, which cam, by 130

its engagement with said pin, causes the starting clutch 40 to move away from and out of engagement with the driving clutch 35. This disconnects the mechanism from the source of power, so that it will be disposed to stop; and the engagement of the rear end of notch 47^a with the toe 44^c causes the cam shaft to stop in exactly the right position.

10 While the cam shaft is in rotation it produces the following results: It, first, turns cam 108 so as to release the auxiliary line carrier from restraint. Thereupon the auxiliary line carrier spring 112, acting 15 through the described train of mechanism, causes such a movement of the auxiliary line carrier to the right, as will cause its push bar 24 to move into contact with the left matrix on the distributing rail, and will 20 thereafter continue to move the matrix line in the distributing direction until the auxiliary line carrier is again drawn to the left by said cam 108. It will be understood that the power to move the auxiliary line carrier 25 mechanism to the right is applied to the sliding bar 20, which first moves a short distance independently of the slide. By so moving, it releases the upper link 22 from restraint, and the spring 25 causes said link 30 to so swing as to carry the auxiliary line carrier push bar 24 up through the slot in the distributing rail into operative position. This being accomplished, a further movement of the sliding bar to the right will 35 cause a corresponding movement of the slide, and all the parts supported thereon. As the cam shaft rotates, the cam 72^a will move the elevator clutch lever so as to carry the elevator clutch forward into engagement 40 with the jaws of the gear 66, whereupon the elevator shaft will begin to rotate clockwise (when viewed from the front) and the elevator will begin to rise. At about the same time the cam 86 will begin to act on the segment frame 87, and to swing it in such wise 45 that the line carrier mechanism is drawn to the left until its pressure plate 5 is at the left of the path in which the elevator moves upward. Just before the elevator reaches 50 the top of its path a shoulder 1^a thereon will engage the plunger latch 82 and push it back, and then said latch will fly forward under said shoulder and temporarily act to hold the elevator up and in exactly the 55 proper position relative to the distributing rail 16, when the elevator is settled back so as to rest upon said plunger latch. When the elevator has passed the plunger latch in its upward movement the cam 72^a will 60 have come to such position that the clutch lever will be moved to carry the elevator clutch into intermediate position, whereupon the elevator shaft stops its rotation. This condition of the mechanism is maintained 65 while cam 86 backs off from the segment 87

and allows the spring 88 to so swing it as to move the line carrier to the right. By this movement the line carrier will sweep the matrix line from the elevator onto the distributing rail and along said rail to the distributing mechanism. Thereafter the cam 72^a by its advance allows the elevator clutch lever to be moved by its spring so as to move the elevator clutch rearward into clutching engagement with the gear 67. This movement of the clutch operating lever withdraws the latching plunger; whereupon the elevator clutch shaft begins to rotate counter clockwise and moves the elevator down. As the elevator is reaching its down position the cam 72^a will move the clutch operating lever 75 80 85 so as to carry the elevator clutch into its neutral position which causes the elevator shaft to cease rotation. In the meantime cam 108 has moved the auxiliary line carrier mechanism to the left; that is to its initial position. When these results have been accomplished the cam shaft will be near the end of its single revolution; the toe 44^c will drop into notch 47^a, the pin 45 will move 90 95 into position to be engaged by the spiral cam 40^c, and this engagement will cause the endwise movement of the starting clutch and disconnect it from the driving clutch. The mechanism having performed its functions will now come to rest.

A bracket 43 is fixed to the auxiliary line carrier slide 21 and extends upward and has pivoted to its upper end on a horizontal rearwardly extended pivot the arm 42, 10 which arm is under the influence of a spring 44 tending to rock it to carry its right end downward as far as it can go until a rearwardly extended tail piece 47 engages a stop pin 46 fixed to the bracket 43. This arm 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 Having described our invention, we claim:

1. In a line casting machine, the combination of a vertically movable elevator which is provided with a support for a matrix line, an elevated support which is adapted to guide a line of matrices toward the distributing mechanism, and which the elevator support will be aligned with when the elevator is raised, a horizontally movable line carrier adapted to sweep the matrix line from the elevator support onto and along the elevated support, a horizontally movable auxiliary line carrier, springs for independently moving said line carriers in

the matrix distributing direction, and means for moving them in the contrary direction, substantially as specified.

2. In a line casting machine, the combination of a vertically movable elevator which is provided with a support for a matrix line, an elevated support which is adapted to guide a line of matrices toward the distributing mechanism and which the elevator support will be alined with when the elevator is raised, a horizontally movable line carrier adapted to sweep the matrix line from the elevator support onto and along the elevated support, a horizontally movable auxiliary line carrier, springs for moving said line carriers in the matrix distributing direction, cams for respectively moving said line carriers in the contrary direction, driving mechanism which includes a clutch for turning said cams, means for causing said clutch to close, and a cam turning with the other cams for opening said clutch.

3. In a line casting machine, an auxiliary line carrier comprising a slide movable in horizontal guideways, a sliding bar supported by and having a limited horizontal movement on said slide, mechanism connected with the said sliding bar for moving the auxiliary line carrier back and forth, a push arm movably connected with said slide and adapted to project into the path which a line of matrices must travel in going to the distributing mechanism, a spring normally holding said arm in operative position, and means operated by the sliding bar for drawing said arm to an inoperative position.

4. In a line casting machine, an auxiliary line carrier comprising a slide movable in horizontal guideways, a sliding bar supported by and having a limited horizontal movement on said slide, mechanism connected with the said sliding bar for moving the auxiliary line carrier back and forth, two parallel links pivoted to said slide, one being provided with an angle arm, a line carrier push bar pivotally connected to the free ends of said parallel links, a spring acting to swing said links in a direction which carries the push bar to an operative position, and a shoulder fixed to the sliding bar and adapted to engage the angle arm of one of said links whereby the same may be rocked to draw the push bar to an inoperative position.

5. In a line casting machine, an auxiliary line carrier comprising a slide movable in horizontal guideways, a sliding bar supported by and having a limited horizontal movement on said slide, mechanism connected with the said sliding bar for moving the auxiliary line carrier back and forth, two parallel links pivoted to said slide, one being provided with an angle arm, a line carrier push bar pivotally connected to the free ends of said parallel links, a spring

acting to swing said links in a direction which carries the push bar to an operative position, and a shoulder fixed to the sliding bar and adapted to engage the angle arm of one of said links whereby the same may be rocked to draw the push bar to an inoperative position, a cam engaging a part of the mechanism which is connected with said sliding bar whereby the auxiliary line carrier may be retracted, and a spring acting upon said mechanism for moving the auxiliary line carrier in the contrary direction.

6. In a line casting machine having a substantially horizontal support on which a matrix line may move toward the distributing mechanism, an auxiliary line carrier comprising a slide, a push bar movably connected therewith, a spring for moving said push bar to carry its end into the path the matrices may travel while moving along said support, a bracket fixed to the auxiliary line carrier slide, a spring actuated arm pivoted thereto and normally lying in such a position that its end projects into the path in which the upper part of the matrix line must move, a spring for moving the auxiliary line carrier in the matrix distributing direction, and means including a cam for moving it in the contrary direction.

7. In a line casting machine, the combination of a vertically movable elevator, a rotatable elevator shaft, mechanism operated thereby for moving the elevator, mechanisms for turning said elevator shaft in opposite directions, a clutch for connecting said elevator shaft with either of said turning mechanisms, a horizontally movable line carrier for sweeping the matrix line from the elevator onto and along a support for said matrix lines, a cam shaft, a cam thereon for actuating the line carrier in one direction, a spring for actuating it in the contrary direction, a cam on said cam shaft for operating said elevator clutch, a spring latch adapted to engage the elevator to temporarily hold it in its elevated position, and mechanism operated by said clutch operating mechanism for withdrawing said latch.

8. In a line casting machine, the combination of a rotating driving member, a rotatable starting shaft, a clutch for connecting said starting shaft and driving member, an elevator shaft, two trains of mechanism intermediate of said starting shaft and elevator shaft whereby the latter may be turned in reverse directions, a clutch for connecting either train of mechanism with the elevator shaft, a spring actuating said starting clutch in the clutching direction, a starting lever normally restraining the clutch movement of said starting clutch, a cam shaft, power transmitting mechanism intermediate of the starting shaft and the cam shaft, a cam on the cam shaft, mechanism operated thereby for moving the ele-

vator clutch, and mechanism carried by said cam shaft adapted to control the return of the starting lever to its normal position in which it holds the starting clutch out of 5 action.

9. In a line casting machine, the combination of a rotating driving member, a rotatable starting shaft, a clutch for connecting said starting shaft and driving member, an 10 elevator shaft, two trains of mechanism intermediate of said starting shaft and elevator shaft whereby the latter may be turned in reverse directions, an elevator clutch for connecting either train of mechanism 15 with the elevator shaft, a spring for actuating said starting clutch in the clutching direction, a starting lever normally restraining the clutching movement of said starting clutch, a cam shaft, power transmitting mechanism intermediate of the starting shaft and the cam shaft, a cam on the cam shaft, mechanism operated thereby for moving the elevator clutch, mechanism carried by said cam shaft adapted to control 20 the return of the starting lever to its normal position in which it holds the starting clutch out of action, a line carrier, a cam on said cam shaft by which the line carrier is moved in one direction, and a spring for 25

moving the line carrier in the contrary direction. 30

10. In a line casting machine, the combination of a vertically movable elevator, an elevator shaft, two trains of mechanism adapted to turn said elevator shaft in 35 reverse directions, a clutch for connecting said elevator shaft with either train of mechanism, a cam shaft, clutch operating mechanism, a cam on the cam shaft for actuating said clutch operating mechanism, a line carrier, a sprocket chain with which the line carrier is connected, a driving sprocket, a rotatable shaft to which the driving sprocket is secured, a swinging spring-actuated gear segment, a cam fixed to said cam 40 shaft for moving the same in opposition to its spring, and a train of gears intermediate of said segment gear and of said sprocket shaft.

In testimony whereof, we hereunto affix 5 our signatures in the presence of two witnesses.

ARTHUR W. LE BOEUF.
JOSEPH B. ARMITAGE.
